UNITED STATES PATENT OFFICE.

EDGAR J. RICHARDSON, OF SIOUX CITY, IOWA.

AUTOMOBILE-RADIATOR.

1,103,840.

Specification of Letters Patent. Patented July 14, 1914.

Application filed May 14, 1913. Serial No. 767,635.

To all whom it may concern:

Be it known that I, EDGAR J. RICHARDSON, a citizen of the United States, residing at Sioux City, in the county of Woodbury 5 and State of Iowa, have invented new and useful Improvements in Automobile-Radiators, of which the following is a specification.

This invention provides a radiator for use 10 in connection with internal combustion engines for cooling the water circulating through the jacket of the engine cylinder to prevent overheating.

In its specific adaptation the invention 15 provides a radiator for automobiles, said radiator comprising means to prevent the chilling or freezing of the water in extreme cold when the machine is at rest.

A further purpose of the invention is the 20 provision of a radiator which presents a maximum cooling surface for radiating heat in warm weather, thereby preventing overheating of the water and the conversion of the same into steam.

The invention consists of the novel features, details of construction and combination of parts, which hereinafter will be more particularly set forth, illustrated in the accompanying drawings, and pointed out in 25 the appended claim.

Referring to the drawings, forming a part of the specification, Figure 1 is a perspective view of an automobile radiator embodying the invention. Fig. 2 is a rear view. Fig. 3 is a vertical central longitudinal section. Fig. 4 is a transverse section on the line $y-y$ of Fig. 2. Fig. 5 is a horizontal section on the line $x-x$ of Fig. 2. Fig. 6 is a front view, the casing being removed. Fig. 7 is a rear view of part of the casing, showing more clearly the sliding sectional door for closing the opening in the front of the casing. Fig. 8 is a view of the radiator inverted. Fig. 9 is a detail section 40 of the lower portion of the radiator showing the front end of the doors dropped into vertical position.

Corresponding and like parts are referred to in the following description, and indicated in all the views of the drawings, by 45 the same reference characters.

The radiator may be of any construction or design and comprises an upper water compartment 1, a lower water compartment 2 and intermediate tubes 3 connecting such compartments. Heat radiating fins 4 are

interposed between the water tubes 3 and assist materially in cooling the water circulating through the tubes 3 when the radiator is in active operation.

A heating chamber 5 is located below the water compartment 2 and is adapted to receive heating means of any nature to prevent the chilling or freezing of the water in cold weather. In the preferable form the 60 heater consists of two lamps 6 which are placed in opposite ends of the heating chamber 5 and secured therein by any suitable means. The heating chamber is closed at its front and bottom by means of doors 7 and 8 which may be removable, the front door 7 being hinged to swing downward at its upper edge. The sides and bottom of the heating chamber are provided with openings for the ingress of air to support combustion when the lamps 6 are lighted.

Air tubes 9 extend through the water tubes 3 and the water compartments 1 and 2 and connect with the outer walls thereof, as shown most clearly in Fig. 3. The lower 65 ends of the air tubes 9 are spaced from the top of the water compartment 2 and make close connection with the bottom of such compartment, thereby admitting of the water circulating from the compartment 2 70 through the water tubes. The upper ends of the air tubes 9 pass loosely through the bottom of the upper compartment 1 and make close connection with the top of such compartment so as not to interfere with the 75 circulation of the water between the compartment 1 and water tubes 3. Other air tubes 10 and 11 lead from the heating chamber 5, the air tubes 10 being at the sides of the radiator and having their upper ends 80 opening through the top thereof. The intermediate air tubes 11 connect at their upper ends with the air spaces 12 above the water compartment 1 with which the upper ends of the air tubes 9 communicate. The 85 filling tube 13 connects with a water space 14 located between the air spaces 12. The walls inclosing the air spaces 12 are provided with openings for the escape of hot air. Plates 15 close the tops of the air spaces 105 12 and are made removable to admit of access being had readily to such air spaces for any purpose. Coupling ends 16 communicate with the air spaces 12 and are adapted to make connection with pipes or tubes leading to the space surrounding the carburetor 110 to prevent chilling of the latter in cold

weather so that the engine may be easily started. Other coupling ends 17 connect with the water compartments 1 and 2 and are adapted to have the pipes leading to the 5 water jacket of the engine connected thereto.

A casing 18 incloses the main body of the radiator and is provided in its front with an opening opposite the space formed between the upper and lower water compartments so that air may pass freely through 10 the tubes and heat radiating fins. The opening in the front of the casing is protected by means of a screen 19. In cold weather or when it is required to retain the 15 heat the opening in the front of the casing may be closed by sectional sliding doors 20 which are mounted in guides 21 arranged above and below the opening. The doors 20 are adapted to be secured either in closed or 20 open position by means of knobs 22 which are threaded to stems attached to the outermost door sections, the stems of the knobs operating in a slot 23 formed in the screen 19. When the knobs 22 are loosened the 25 doors may be slid open or closed and are held in the required position by tightening the knobs so as to clamp the part of the screen 19 adjacent the slot 23 between such knobs and the outer door sections. Openings are formed in the side walls of the 30 spaces formed above and below the water compartments 1 and 2 so that air may have unobstructed passage. The casing 18 protects the main portion of the radiator and 35 gives a finished appearance thereto. A door 24 is provided in the lower portion of the front of the casing opposite the door 7 so that access may be had to the heating chamber 5 for lighting or trimming the lamps. The casing is readily removable, thereby 40 facilitating access to the main portion of the radiator for repairs or other purpose. An overflow pipe 25 extends into the water space 14 so as to carry off excess of water 45 or any vapor that may be generated. A drain cock 26 connects with the lower portion of the water compartment 2 for drawing off all water from the radiator when it is required to empty the same.

In cold weather the water is prevented 50 from chilling and freezing in the radiator by lighting the lamps 6 or having recourse to the particular form of heater located in the heating chamber 5. The warm air after 55 leaving the heating chamber 5 passes up-

wardly through the air tubes 9, 10 and 11, thereby warming the water. When the heating feature of the radiator is in active operation the doors 20 are closed as also the doors 24 and 7. In warm weather or when 60 it is desirable to obtain a maximum amount of heat radiating surface the lamps are removed or the heater dispensed with, the doors 7 and 8 being removed and the door 24 thrown open so that cool air may have 65 an unobstructed passage through the air tubes, thereby supplementing the air passing upon the exterior of the water tubes and water compartments, with the result that the water is prevented from heating excessively. It is understood that the doors 20 are slid into open position so that the cool air may circulate freely through the water tubes and heat radiating fins 4.

From the foregoing description, taken in 75 connection with the accompanying drawings, the advantages of the construction and of the method of operation will be readily apparent to those skilled in the art to which the invention appertains, and while I have 80 described the principle of operation of the invention, together with the device which I now consider to be the best embodiment thereof, I desire to have it understood that the device shown is merely illustrative, and 85 that such changes may be made when desired as are within the scope of the claim appended hereto.

Having thus described the invention what is claimed as new, is:—

A radiator comprising upper and lower water compartments, intermediate water tubes connecting such compartments, a heating chamber beneath the lower compartment having door covered openings in its front 95 and bottom, an air space above the upper compartment, air tubes connecting the heating chamber and air space, a casing inclosing the compartments and intermediate connecting tubes, and a door in the lower portion of the front of the casing opposite the door opening in the front of the heating chamber.

In testimony whereof I affix my signature in presence of two witnesses.

EDGAR J. RICHARDSON.
